MAGNETIC TAPE TELEVISION APPARATUS

Orville W. Larson, Elmhurst, Ill., assignor to Ampex
Corporation, Redwood City, Calif.

Filed Aug. 27, 1970, Ser. No. 24,719

Term of patent 14 years

Int. Cl. D14—01, 03

U.S. Cl. D26—14

FIG. 1

FIG. 2

FIG. 1 is a perspective view of the front, top and left side of a magnetic tape television apparatus embodying my new design; and

FIG. 2 is a perspective view of the bottom, rear and left side of the apparatus of FIG. 1, the right side being a mirror image of the left side.

I claim:

The ornamental design for a magnetic tape television apparatus, substantially as shown and described.
